SAIL CONTROL DEVICE

Harry Melges, Zenda, Wis.

Application December 20, 1948, Serial No. 66,200

5 Claims. (Cl. 114—103)

1

The present invention relates to sails and more particularly to sails used on pleasure craft, such as racing sail yachts and the like.

Sails in common use on pleasure craft today, and especially those sails which have the luff or leading edge secured to a mast, are predominantly of the triangular type having three sides only. It often becomes necessary to reduce the area or size of a sail, as when due to excessive wind conditions, and this can only be done by lowering the sail and reefing it—a method of reducing sail area which has remained unchanged for generations—or by substituting a smaller sail. Both methods take considerable man-power, and often are hazardous to the crew members involved. Furthermore, a boat which is sailing with or away from the wind can safely and efficiently carry more sail area than when it is sailing close hauled or tacking into or toward the wind. Thus, when a boat is sailing close hauled in an excessive wind, it should reduce its sail area to gain efficiency and forward driving power, and if the wind velocity decreases or the boat changes its course so that it is no longer sailing close hauled it is desirable to increase the sail area.

The usual system of reefing a sail is time consuming, hazardous, injurious to sails, and requires considerable man-power. When racing, sail boats often sail a three legged course, one leg of which is opposed to the direction of the wind and requiring close hauled sailing and tacking, and the other two legs consisting of sailing away from the wind and with the wind abeam or at right angles. A sail boat can safely and efficiently carry more sail area on the latter two legs than it can on the close hauled leg, and if it is advisable to reef the sails on the close hauled leg, as it often is, and restore the sail to its full size for use on the other two legs it can readily be seen that there is much valuable time, energy, and effort consumed, plus danger to personnel and damage to sails. An additional problem to racing sailors is the fact that, when sailing close hauled in a strong wind, a relatively flat sail is more efficient than a fully formed or drafty sail having considerable belly, but when sailing away from the wind, or with the wind at right angles to the course of the boat, the reverse is true and the fully formed drafty sail is then the more efficient with resulting increase in boat speed.

The objects of my invention are to overcome such objections as just noted by providing a sail having means to alter its shape and deflect the air flow thereon so as to render a portion of the

2

sail inoperative, when desired, and without resorting to the necessity of reefing. The present invention offers most of the advantages of a reefed sail when close hauled and none of the disadvantages. Another object is to provide a sail having means for controlling and altering its draft or curvature so as to increase or decrease the amount of draft at will to conform efficiently to varying wind conditions.

10 With the above and other objects in view, my invention consists in the construction and novel combination and arrangement of parts herein-after fully described, illustrated in the accompanying drawings and pointed out in the claims hereto appended, it being understood that various changes in the form, proportions, and minor details of construction, within the scope of the claims, may be resorted to without departing from the spirit or sacrificing any of the advantages of the invention.

15 In the drawings, Fig. 1 is a side elevational view of a boat with a sail embodying my invention; and Fig. 2 is a similar view wherein my invention is shown in modified form.

20 The present invention may advantageously be applied to a sail S of the type in common use, having three sides, the leech x, the luff l which is slidably secured to a mast M, the foot f which is secured to a boom B, and three corners—the 25 tack T, the clew C, and the head H. The leech x may contain the usual stiffening battens 10 which are held in place by fabric pockets in the customary manner. The function of the battens 30 is to keep the curved roach r portion of the sail from collapsing inwardly. A sheet rope s which extends between the boom B and a cleat v on the boat deck serve to hold the boom in a desired 35 adjusted position.

40 The features which are special to my invention comprise a guiding means which may take the form of a narrow flexible strip 11 secured to one side of the sail S, as by sewing its side edges thereto. This guiding strip extends from a point at or adjacent the head H to the foot f at a point 45 which is spaced inwardly from the clew C. A flexible cord 12 of wire, rope, or other suitable material is secured to the head portion of the sail and extended downwardly parallel to the sail slidably through the tunnel or pocket formed 50 between the strip and the sail S, and upon emerging from the lower end of the strip passes through a pulley 13 which is secured to the boom B and substantially in line with the strip as shown in Fig. 1, and thence to a cleat 14 also 55 cured to the boom where its free end is made fast.

When the cord is tightened, by taking in on the free end, the curvature or belly of the sail S is reduced and brought more nearly into a flat plane along the line of the cord, and this has the effect of allowing the after portion 15 of the sail which lies to the rear of the cord and which contains the battens and comprises the roach r, to slacken and sag away to leeward in response to wind pressure, thus removing it from a position of resistance to the wind, which resistance is further diminished because the wind is deflected outwardly and away from the after portion 15 of the sail. The effective sail area is thereby reduced to that portion of the sail which lies forwardly of the cord.

The strip may optionally be extended along the sail S through a curved line bowed away from the leech as shown at 21 in Fig. 2, and when the cord 22 is tightened it will reduce the amount of draft or belly by stretching the sail rearwardly away from the mast and toward the straightened cord. This provides an excellent means of controlling the draft or curvature to suit the wind conditions, thus increasing the air flow efficiency of the sail. The cord may be secured at either end and adjusted from the opposite end. Fig. 1 illustrates my preferred method whereby one end of the cord is secured to the head H of the sail and is adjusted from the lower end adjacent the foot f of the sail. Fig. 2, on the other hand, shows this in reverse with one end of the cord 22 attached to the boom B, thence extended upwardly adjacent the sail to a pulley 23 at the head H, then downwardly adjacent the mast to a cleat 24 where it is adjustably secured. Likewise both ends may be adjustably secured for convenient handling at the option of the operator. Fig. 2 also illustrates additional means of retaining the cord 22 adjacent the sail as for example by rings 25 and eyes 26.

From the foregoing description and discussion, it will be seen that my invention simultaneously serves two outstanding useful and desirable functions by (a) providing a sail having flexible means whereby the curvature and air flow properties can be quickly adjusted and adapted to suit varying wind conditions, and (b) providing a sail having means whereby part of the sail may easily and quickly be rendered inoperative for the purpose of lessening wind resistance thereto.

It is to be understood that the present invention is not a reefing device although it partially achieves the same result. The distance of the cord at the point where it meets the boom B from the clew C of the sail, and the amount of curve followed by the strip when it is sewn to the sail, must, of necessity, vary with the size of the sail, the amount of roach curve, the length of battens, and the amount of draft or belly built into the sail, as all these factors must be co-ordinated to attain maximum sail efficiency.

I claim:

1. For use with a sailing boat having an up-standing mast and a boom extended rearwardly therefrom, a triangular fore and aft sail having a head, a luff, a foot, and a leech, the luff being secured to the mast and the foot to the boom, a flexible cord having one end portion secured to the boom extending upwardly medially of the luff and leech to the sail head thence downwardly adjacent the mast to the lower end portion thereof, means for adjustably securing the free end of the cord, and means on the sail for re-

taining the cord parallel to and adjacent the sail for substantially the full distance between the sail foot and the sail head with capacity for endwise movement of the cord relative thereto.

2. For use with a sailing boat having an up-standing mast and a boom extended rearwardly therefrom, a triangular fore and aft sail having a head, a luff, a foot and a leech, the luff being secured to the mast and the foot to the boom, a flexible cord supported at the head of the sail and extending downwardly therefrom parallel to and adjacent one side of the sail medially of the luff and leech thereof to the boom and nearer the rearward end thereof, means for adjustably securing the lower end portion of the cord to the boom, and an elongated strip of flexible material extending from the head to the foot of the sail and having its longitudinal edges secured to the sail so as to enclose the cord therebetween.

20 3. For use with a sailing boat having an up-standing mast and a boom extended rearwardly therefrom, a triangular fore and aft sail having a head, a luff, a foot, and a leech, the luff being secured to the mast and the foot to the boom, a plurality of rings secured to the sail extending in a line from the sail head downwardly medially of the luff and leech to the sail foot, a flexible cord supported at the sail head and extending downwardly therefrom through the rings to the boom, and means for adjustably securing the lower end portion of the cord to the boom.

25 4. For use with a sailing boat having an up-standing mast and a boom extended rearwardly therefrom, a triangular fore and aft sail having a head, a luff, a foot, and a leech, the luff being secured to the mast and the foot to the boom, a flexible cord supported at the sail head and extending downwardly therefrom medially of the luff and leech to the boom, means for adjustably securing the lower end portion of the cord to the boom, and means on the sail for holding the cord parallel to and adjacent the sail for substantially the entire distance between the sail head and the sail foot with capacity for endwise movement of the cord.

45 5. For use with a sailing boat having an up-standing mast and a boom extending rearwardly therefrom, a triangular fore and aft sail having a head, a luff, a foot, and a leech, the luff being secured to the mast and the foot to the boom, a flexible cord supported at the head of the sail and extending downwardly therefrom parallel to and adjacent one side of the sail medially of the luff and leech thereof to the boom and nearer the rearward end thereof, means for adjustably securing the lower end portion of the cord to the boom, and means on the sail for retaining the cord parallel to and adjacent the sail for substantially the full distance between the sail foot and the sail head with capacity for endwise movement of the cord relative thereto.
